ABSTRACT: Adjustable headgear is disclosed which includes a first or occipital strap having an upper end and a lower end and is adapted to extend from the back of the head of the wearer upward to the top area of the head. A second strap having an upper end and a lower end is adapted to extend from the right side of the head of the wearer upward to the top area of the head. A third strap having an upper end and a lower end is adapted to extend from the left side of the head of the wearer upward to the top area of the head. A top adjustment piece has slits therein through which the upper ends of the straps pass so that the length of each strap from its lower end up to the adjustment piece can be adjusted by sliding the strap through the slits in the adjustment piece. Backstrap means has forward end portions connected to the lower ends of the second and third straps and extends around from the lower end of the second strap to the lower end of the third strap. The lower end of the first strap is connected to the strap means generally centrally of the latter.

PATENTED MAR 23 1971

3,571,930

FIG. 1

FIG. 2

ADJUSTABLE HEAD GEAR

BACKGROUND OF THE INVENTION

This invention relates to orthodontic appliances and more particularly to orthodontic headgear for use in connection with extra-oral traction procedures.

Various types of orthodontic headgear are known for use in connection with extra-oral traction procedures, for example with so-called arch bands to apply traction for orthodontic purposes. The headgear may be classified according to its position on the head of the wearer: high-pull headgear which is frequently used to apply traction to a maxillary arch (upper teeth) band; low-pull headgear which is suitable for applying traction to either a maxillary or a mandibular arch (lower teeth) band, or combination headgear which may be referred to as low- and high-pull headgear. Frequently the high-pull headgear is used with a chin cup to correct jaw movements and occlusions, particularly class three malocclusions, and also as an isometric face muscle exerciser to tone up physiognomies. The head gear in all cases must be fitted to the head of the wearer in order to assure proper alignment of the appliance and the proper application of force thereto. This is frequently done by simply cutting the ends of the device to the desired length and stapling them in position. Once this is done the device cannot be changed as the size of the user's head changes. It is difficult to get the various pieces precisely cut and aligned for stapling. Alternately the fitter of orthodontic appliances may carry a variety of sizes of headgear which will only approximately fit the head of any particular user.

SUMMARY OF THE INVENTION

It is an object of the instant invention to provide an adjustable headgear useful in extra-oral traction procedures which is adjustable in all dimensions. This advantageously eliminates the necessity of stocking various sizes of headgear. It is a further object of the instant invention to provide adjustable orthodontic headgear which without cutting may be adjusted to fit any size or shape head with a minimum of fitting time. The instant invention advantageously is adaptable to all types of headgear, such as low-pull, high-pull, intermediate-pull, and low- and high-pull. It is a further object of the instant invention to provide adjustable orthodontic traction headgear which may be fitted to practically any type extra-oral traction device.

The instant invention relates to adjustable headgear which includes an occipital or first strap having an upper end and a lower end and adapted to extend from the back of the head of the wearer upward to the top area of the head. A second strap having an upper end and a lower end is adapted to extend from the right side of the head of the wearer upward to the top area of the head, also herein referred to as a right side strap. A third strap having an upper end and a lower end is adapted to extend from the left side of the head of the wearer upward to the top area of the head, also hereinafter referred to as a left-side strap. A top adjustment piece has slits therein through which the upper ends of the straps pass so that the length of each strap from its lower end up to the adjustment piece can be adjusted by sliding the strap through the slits in the adjustment piece and then anchoring it. Backstrap means has forward end portions connected to the lower ends of the second and third straps and extend around from the lower end of the second strap to the lower end of the third strap. The lower end of the first strap is connected to the strap means generally centrally of the latter. Other objects and features will be in part apparent and in part pointed out hereinafter.

BRIEF DESCRIPTION OF THE DRAWINGS

FIG. 1 is a rear elevational view toward the side illustrating a high-pull headgear of this invention as it is worn on the head with a chin cup;

FIG. 2 is a view similar to FIG. 1 of the invention removed from a head;

FIG. 3 is a side elevational view illustrating a combination high- and low-pull headgear of this invention as it is worn on the head;

FIG. 4 is a back elevational view of FIG. 3;

FIG. 5 is a back elevational view toward the side of a low-pull headgear embodying this invention as it is worn on the head; and

FIG. 6 is a back elevational view toward the side of a variation of high-pull headgear embodying the instant invention.

Corresponding reference characters indicate corresponding parts throughout the several views of the drawings.

DESCRIPTION OF THE PREFERRED EMBODIMENT

Referring particularly to FIGS. 1 and 2, it may be seen that the high-pull headgear according to the instant invention comprises a first occipital strap 1 having an upper end 3 and a lower end 5 adapted to extend from the back of the head (the occiput) of the wearer upward to the top area of the head. A second or right side strap 7 having an upper end 9 and a lower end 11 extends from the right side of the head of the wearer upward to the top area of the head. A third or left-side strap 13, also having an upper end 15 and a lower end 17, extends from the left side of the head of the wearer upward to the top of the head. A top adjustment piece 19 has a first pair of slits S1 extending generally parallel to one another adjacent the left side thereof and a second pair of slits S2 extending generally parallel to one another and to the slits of the first pair adjacent the right side thereof. The first pair defines a left-side loop 20L and the second pair defines a right side loop 20R of the material. A third pair of slits S3 crosswise of the top adjustment piece defines a crosswise loop 20C. The upper end portion of the left-side strap 13 extends across the adjustment piece from left to right through the left-side loop 20L and then through the right side loop 20R, and the upper end portion of the right side strap extends across the adjustment piece from right to left through the right side loop 20R and then through the left-side loop 20L. The upper end portion of the occipital strap 1 extends through the crosswise loop 20R between the left-side and right side loops. This enables adjustment of the length of each strap 1, 7 and 13 from its lower end 5, 11, 17 up to the adjustment piece by sliding the straps through the loops.

Means such as staples 21 similar to those used in a conventional hand stapler fasten the straps 1, 7 and 13 and the adjustment piece 19 together in the adjusted position.

Backstrap means shown as comprising a first backstrap 23 and a second backstrap 25 connect the lower ends 11 and 17 of third strap 13 and second strap 7. As shown, forward end portion 29 of first backstrap 23 is connected to the lower end 11 of right side strap 7 as by rivet 31. First backstrap 23 then extends back from right side strap 7 around to the back part of the head of the wearer. Similarly, forward end portion 43 of second backstrap 25 is connected to the lower end 17 of left-side strap 13 as by rivet 35 and extends around to the back part of the head of the wearer. The free ends 37 and 39 of back straps 23 and 25 pass through a loop 27 formed by slits in the lower end 5 of occipital strap 1 so that the lower end of the first occipital strap 1 is connected to the strap means generally centrally thereof. The length of each back strap 23 or 25 around to the lower end 5 of the first occipital strap 1 can be adjusted by sliding the backstrap through loop 27. Means such as staples 41 fasten the back straps 23 and 25 and occipital strap 1 together in the desired adjusted position.

The straps and adjustment piece are desirably made of a flexible plastic material such as vinyl plastic.

Attached to the lower ends 11 and 17 of second and third straps 7 and 13 at rivets 31 and 35 are closed hooks 43 which in turn are attached to stretchable webbings 45 which are adjustable in length by means of cinch-type clamps 46. The two webbings 45 extend to and are attached at their opposite ends to chin cup 47. Chin cup 47 is molded from a suitable flexible material such as by vacuum-forming plastic.

Referring now to FIGS. 3 and 4, the use of the instant invention to provide orthodontic adjustable headgear for a different type of extra-oral traction arrangement may be seen. As shown in these FIGS., left-side strap 13, and so also right side strap 7, are riveted at their lower ends 17 and 11, respectively, to the yokes 49 and 51 of an orthodontic device of the type described in U.S. Pat. No. 3,203,099 to Sebastiao Interlandi. The first backstrap 23 and the second backstrap 25 have their forward end portions 29 and 33 riveted to the lower ends of yokes 51, 49, respectively. Thus the right side and left-side straps 7 and 13 are each attached to the backstrap means constituted by the two backstraps 23, 25 by the yokes 49, 51 of the orthodontic appliance.

Each yoke 49, 51 has a series of notches 53 in its posterior (rear) edge. Notches 53 constitute recesses for receiving one or more traction-applying elastic bands (rubberbands) 55. One end of each elastic band 55 is adapted to be looped around one or more tongue portions formed between neighboring notches 53 and drawn forwardly into the notches 53. The other end of each elastic band 55 is adapted to be connected to a face bow as indicated at 57 or 59. Each bow 57 is formed in the shape of a hook and is adapted to be attached to an arch band (not shown) for a maxillary arch (the upper teeth), for example. Traction is exerted on the arch band by the elastic band 55 acting through the face bow 57. A tubular sleeve 61 formed of plastic, for example, may be provided on the shank of each bow 57 to prevent irritation of the cheeks by bow 57. Bow 59 is adapted to be attached to the arch band in the same manner as bow 57. Traction is exerted on the arch band by the elastic band 55 acting on the outer end of bow 59.

FIG. 5 illustrates the invention as applied to a low-pull-type headgear. In this embodiment it will be observed that the length of each backstrap 23, 25 is not adjustable. The backstraps 23, 25 are sewn to the lower end 5 of the first occipital strap 1. As shown, the forward end portion 33 of a second backstrap 25 is sewn to the lower end 17 of left-side strap 13. The switching of the straps together is done so that the stitches 63 attach the straps to neck pad 65. Neck pad 65 has loops 67 provided therein. Extending through the loops are the stretchable webbings 69 which are adjustable in length by means of cinch-type clamps 70 of an orthodontic appliance. The rearward end portions 71 of webbings 69 are each attached by means of closed hooks 73 to rivets 75 driven through the backstraps 23, 25 and neck pad 65. Face bow 77 of an orthodontic appliance is attached to the forward end 79 of webbings 69 as by hooks 81.

FIG. 6 illustrates another embodiment of the instant invention as applied to high-pull headgear. The construction of the adjustable headgear is similar to that shown in FIGS. 1 and 2. Attached to the ends of the backstrap means, i.e., forward end portions 29 and 33 of a first backstrap 23 and second backstrap 25 adjacent the lower ends 11 and 17 of right side strap 7 and left-side strap 13 as by rivets 83, are tubular sleeves 85 constituting guides for face bows 87. Each face bow 87 is hooked to a rubberband 89 which in turn is attached to tubular sleeve 85 by a rivet 93. Tubular sleeve 85 also helps to prevent irritation of the cheeks of the wearer by face bow 87 of the orthodontic appliance.

In view of the above, it will be seen that the several objects of the invention are achieved and other advantageous results attained.

As various changes can be made in the above constructions without departing from the scope of the invention, it is intended that all matter contained in the above description or shown in the accompanying drawings be interpreted in an il-

lustrative and not in a limiting sense.

I claim:

1. Adjustable headgear which comprises:
an occipital strap having an upper end and a lower end
adapted to extend from the back of the head of the
wearer upward to the top area of the head;
a right side strap having an upper end and a lower end
adapted to extend from the right side of the head of the
wearer upward to the top area of the head;
a left-side strap having an upper end and a lower end
adapted to extend from the left side of the head of the
wearer upward to the top area of the head;
a top adjustment piece formed of flexible plastic material or
the like and having a first pair of slits extending generally
parallel to one another adjacent the left side thereof and a
second pair of slits extending generally parallel to one
another and to the slits of the first pair adjacent the right
side thereof, the first pair defining a left-side loop and the
second pair defining a right side loop of the material, and
a third pair of slits extending crosswise of the top adjust-
ment piece defining a crosswise loop, the upper end portion
of the left-side strap extending across said adjustment
piece from left to right through the left-side loop and then
through the right side loop, and the upper end portion of
the right side strap extending across said adjustment piece
from right to left through the right side loop and then
through the left-side loop, the upper end portion of the
occipital strap extending through said crosswise loop
between the left-side and right side loops; and

backstrap means having forward end portions connected to
the lower ends of the right side and left-side straps and ex-
tending around from the lower end of the right side strap
to the lower end of the left-side strap, the lower end of the
occipital strap being connected to the backstrap means
generally centrally of the latter.

2. The headgear of claim 1 including means for fastening
the straps and adjustment piece together in adjusted position.

3. The headgear of claim 2 wherein the fastening means is a
staple.

4. The headgear of claim 1 wherein the backstrap means
comprises a first backstrap extending back from the right side
strap and a second backstrap extending back from the left-side
strap, and the occipital strap has slits in its lower end defining
a loop through which the free ends of the first and second
backstraps pass so that the length of each backstrap around to
the lower end of the occipital strap can be adjusted by sliding
the backstrap through said slits in the lower end of the occi-
pital strap.

5. The headgear of claim 4 including means for fastening
the backstraps and occipital strap together in the desired position.

6. The headgear of claim 5 wherein the fastening means is a
staple.

7. The headgear of claim 1 wherein the right side and left-
side straps are each attached to the backstrap means by a yoke
of an orthodontic appliance.

8. The headgear of claim 1 including means for attaching an
orthodontic appliance to the lower ends of the right side and
left-side straps.

9. The headgear of claim 1 including means for attaching an
orthodontic appliance to the ends of the backstrap means ad-
jacent the lower ends of the right side and left-side straps.

10. The headgear of claim 1 wherein the straps and adjust-
ment piece are made of a flexible plastic material.
